UNITED STATES PATENT OFFICE.

HENRY C. MINNS, OF TORONTO, ONTARIO, CANADA.

TESTING DEVICE FOR THE IGNITION SYSTEMS OF INTERNAL-COMBUSTION MOTORS.

1,297,715.

Specification of Letters Patent. Patented Mar. 18, 1919.

Application filed January 23, 1919. Serial No. 272,701.

To all whom it may concern:

Be it known that I, HENRY C. MINNS, a resident of the city of Toronto, in the county of York, Province of Ontario, Canada, a subject of the King of Great Britain, have invented certain new and useful Improvements in Testing Devices for the Ignition Systems of Internal-Combustion Motors, of which the following is a specification.

10 In tuning up an internal combustion motor, it is important to ascertain whether conditions are right in the circuits of the electric ignition system and whether the spark plugs themselves are in proper condition.

15 It is my object therefore to devise means for examining, when the motor is turned over, whether a suitable sparking current is flowing to each spark plug and whether any given spark plug is functioning properly.

20 I attain my object by providing a holder in which a spark plug may be removably held, which holder is provided with a stem 25 adapted to fit into the opening for the spark plug in the combustion chamber of the cylinder, whereby the spark plug is held in position for inspection and in electrical connection with the metal of the cylinder.

30 The device is hereinafter more specifically described and illustrated in the accompanying drawings in which

35 Figure 1 is a front elevation, partly broken away, of the device in position in the head of a cylinder of an internal combustion motor with the spark plug in position; and

40 Fig. 2 a side elevation of the same with the spark plug in position.

45 In the drawings like numerals of reference indicate corresponding parts in the different figures.

The main parts of the device are a holder 50 for a spark plug and a stem adapted to fit the spark plug opening in the combustion chamber in the cylinder of an internal combustion motor. In the drawings the stem 1 is shown as a plug adapted to screw into the threaded spark plug opening of the cylinder.

55 Connected with the stem in any suitable manner is a frame 2, having an opening 3 formed therein into which the threaded body of the spark plug may be inserted as shown. Preferably the lower side of the opening is V-shaped as shown and means are provided opposite the V-shaped side to press

the spark plug against the lower side of the opening. A three point contact is thus obtained which will permit of spark plugs of varying diameters being held in position. 60

Preferably the frame 2 is double, that is, it has spaced sides 4 so that the V-shaped side of the opening presents pairs of relatively thin edges adapted to engage in the threads of the body of the spark plug, which 65 increases the security of the holder. Preferably the spark plug is pressed toward the V-shaped side of the opening by means of a lever 5, which is pivoted at 6 between the sides 4 of the frame. A threaded rod 7 is pivotally connected at 8 between the sides 4 and extends up through a hole formed in the lever 5. A nut 9 screwed on the upper end of the rod bears against the upper side of the lever 5. A coil spring 10 is fitted on the rod 7 and engages the under side of the lever 5. 70 It is evident from this construction that the lever may be actuated to clamp a spark plug by rotating the nut 9, and that when the nut is unscrewed the coil spring 10 will disengage the lever from the spark plug. 75

When a spark plug is held in position in one of these holders and the engine turned over, it becomes quite easy to ascertain whether proper current is flowing to the 80 spark plug and whether the spark plug itself is functioning properly, and if not, to make any necessary tests to ascertain where the trouble lies.

85 Preferably with a four cylinder engine all spark plugs are removed and set up in holders. With motors having a larger number of cylinders, any arrangement may be adopted to suit the convenience of the operator. 90

95 What I claim as my invention is:

1. A holder adapted to receive and hold a spark plug and provided with a stem adapted to fit the spark plug opening of the cylinder of an internal combustion motor. 100

2. A holder adapted to receive and hold a spark plug and provided with a stem at right angles to the axis of a spark plug carried by the holder and adapted to fit the spark plug opening of the cylinder of an 105 internal combustion motor.

3. A holder adapted to receive and hold a spark plug and provided with a stem threaded to fit the spark plug opening of the cylinder of an internal combustion motor. 110

4. A spark plug holder comprising a stem adapted to fit the spark plug opening of the

cylinder of an internal combustion motor; a frame connected to the stem having an opening therein to receive a spark plug; and a movable part adapted to secure a spark plug in said opening.

5. A spark plug holder comprising a stem adapted to fit the spark plug opening of the cylinder of an internal combustion motor; a frame connected to the stem having an opening therein to receive a spark plug, said opening being V-shaped at one side; and a movable part adapted to secure a spark plug in said opening, said movable part being located opposite to the V-shaped side.

10. A spark plug holder comprising a stem adapted to fit the spark plug opening of the cylinder of an internal combustion motor;

15. 6. A spark plug holder comprising a stem adapted to fit the spark plug opening of the cylinder of an internal combustion motor;

a double frame connected to the stem having an opening therein to receive a spark plug; 20 and a movable part pivoted between the parts of the frame adapted to secure a spark plug in said opening.

7. A spark plug holder comprising a stem adapted to fit the spark plug opening of the cylinder of an internal combustion motor; a double frame connected to the stem having an opening therein to receive a spark plug; a movable part pivoted between the parts of the frame, screw means adapted to actuate 30 the movable part to secure a spark plug in the opening; and a spring tending to move the movable part to release the spark plug.

Signed at Toronto, Canada, this 15th day of Jan., 1919.

HENRY C. MINNS.
